UNITED STATES PATENT OFFICE.

ARTHUR E. MOODY, OF NEW YORK, N. Y.

DESIGN FOR AN AUTOMOBILE-LAMP.

43,226.

Specification for Design.

Patented Nov. 5, 1912.

Application filed September 4, 1912. Serial No. 718,582. Term of patent 7 years.

To all whom it may concern:

Be it known that I, ARTHUR E. MOODY, a citizen of the United States, and a resident of the city of New York, borough of Manhattan, in the county and State of New York, have invented a new and original Design for Automobile-Lamps, of which the following is a specification, reference being had to the accompanying drawing, forming part thereof.

The figure is a perspective view of an automobile lamp, showing my new design.

I claim:

The ornamental design for an automobile lamp, as shown.

ARTHUR E. MOODY.

Witnesses:

GEO. L. BEELER,
PHILIP D. ROLLHAUS.
